UNITED STATES PATENT OFFICE.

CLYDE J. McNERNY, OF MEMPHIS, TENNESSEE, ASSIGNOR TO HENRY LOEB AND HENRY HURST, BOTH OF MEMPHIS, TENNESSEE.

OIL-BURNER.

1,345,612.

Specification of Letters Patent.

Patented July 6, 1920.

Application filed March 16, 1918. Serial No. 222,813.

To all whom it may concern:

Be it known that I, CLYDE J. McNERNY, a citizen of the United States, and a resident of the city of Memphis, in the county of Shelby and State of Tennessee, have invented certain new and useful Improvements in Oil-Burners, of which the following is a specification.

This invention relates to hydro-carbon oil burners, and one of the objects is to provide means whereby a properly proportioned mixture of air and hydro-carbon may be provided for the purpose of promoting efficient combustion.

Another object of the invention is to provide means whereby the hydro-carbon, before it is mixed with the air, may be vaporized into gaseous or semi-gaseous condition.

Another object of the invention is to provide a burner adapted for use in stoves and furnaces, which will be susceptible of being easily assembled and taken apart for the purpose of inspection or repairs.

It is also the purpose of my invention to generally improve the class of devices to which the invention relates.

In the drawings:

Figure 1 is a plan view of a double burner constructed in accordance with my invention.

Fig. 2 is a side elevational view of the same.

Fig. 3 is a horizontal sectional view on the line 3-3 of Fig. 2.

Fig. 4 is an end view of the burner.

Fig. 5 is a cross-sectional view on the line 5-5 of Fig. 1.

Fig. 6 is a cross-sectional view on the line 6-6 of Fig. 1.

Fig. 7 is a cross-sectional view on the line 7-7 of Fig. 1.

Fig. 8 is a detailed perspective view of the pilot burner for vaporizing the liquid.

And

Fig. 9 is an enlarged cross-sectional view through one of the burner elements.

Referring now to the drawings by numerals of reference, 1 designates an end casting, here shown as substantially rectangular, and provided with a burner supporting end wall 2, which carries the burner elements 3 and 4. Each burner element is substantially tubular and provided with longitudinal partitions 5 and 6, to form upper cham-

bers 7 and lower chambers 8, the lower chambers being adapted to communicate with the upper chambers through the elongated slots 9 and 10 in said partitions, so that vaporized fuel which enters the lower chambers 60 may find access to the upper chambers through the slots 9 and 10 in the partitions, and pass out through the ignition slots 11 formed in the cap of each of the burner elements, as best shown in Figs. 1 and 2. It 65 will be observed that the upper surface of each of the burner elements is substantially corrugated to form lips 12 and 13, which bound the ignition slots 11, so that there will be a plurality of well-defined transverse flames extending throughout each burner element.

The fuel, consisting of the air and gasified hydro-carbon, is introduced into the burner or burner elements through the supply tube 14, having communication with the end air inlet chamber in the end casing 1, through the orifice 15 in the wall 2, the orifice 15 also serving for the introduction of the end of a slip valve 16 which supplies 80 gas to the tube 14, and which may be controlled through the medium of a valve stem 17 accessible on the exterior of the chamber 1, and adapted to be operated by the knurled button 18.

19 and 20 are openings adapted to be controlled by the shutters 21 and 22, whereby varying amounts of air may be admitted to the chamber or casing 1 to mix with the hydro-carbon, the varying proportions being designed to compensate for the varying richness of the gas or vapor. The oil may be fed from any suitable container to the pipe 23 (see Figs. 2, 4 and 5), at a point beneath the chamber 1. The pipe 23 is divided into two branches 24 and 25, the branch 24 being adapted to be opened and closed by a valve 26, and said branch is adapted to run the entire length of the burner and enter a vaporizing tube 27, of greater diameter than the branch pipe 24, said vaporizing tube 27 being slightly to one side and above one of the burner elements, as for example, the burner element 4. The vaporizing tube discharges into the casing of the valve 16 (see Fig. 1). Immediately beneath the vaporizing tube 27 is a pilot burner 28, adapted to communicate with the branch 25, and capable of being opened and closed by a valve 29. The pilot burner is 110

best shown in detail in Fig. 8, as consisting of a tube of relatively small diameter wound intermediate its ends in a series of coils 30, and terminating in a burner tip 31 of any desired construction. The pilot burner may be provided with a casing 32, embracing in part the vaporizing tube 27, and beneath the tip may be arranged a trough or oil pan 33, to receive the oil discharged through the tip 31.

Assuming that all the parts are properly assembled, the operator may first open the valve 29 and admit a sufficient quantity of oil to flow into the pan 33. This may then be ignited, vaporizing the oil flowing through the coils 30, to provide and vaporize fuel. The flame therefrom will act upon the vaporizing tube 27 to heat the same, so that after a sufficient time has elapsed, the valve 26 may be operated to admit liquid fuel through the pipe 24 into vaporizing tube 27, the liquid being vaporized as it passes through the tube adjacent to the pilot burner, after which it will be discharged in a form of vapor into the valve 16; by operating the shutter or shutters the requisite amount of air may be provided for the proper combustion. This gaseous mixture may then enter the supply tube 14 and be discharged into the lower chambers 8 of the burner elements 3 and 4. The partitions 5 and 6, with their peculiarly formed slots, will insure a proper distribution of the mixed gas throughout the upper chambers of the burner elements, so that the gaseous mixture will burn freely at the discharge portions of the slots 11 in an efficient manner.

I claim:

1. An oil burner comprising a mixing chamber, elongated burners carried thereby, a centrally disposed tube interposed between the burners and communicating with them at one end and with the mixing chamber at the other end, longitudinally disposed partitions in the burners dividing them into upper and lower chambers, the partitions having openings whereby the two chambers may communicate, and means for supplying fuel to the central tube.

2. An oil burner comprising a mixing chamber, burner members carried thereby, a tube interposed between said members and communicating with the mixing chamber and with the members, an oil supply pipe, a vaporizing tube into which the pipe discharges, said vaporizing tube leading into the mixing chamber, a branch pipe from the oil supply pipe, having a pilot burner to heat the vaporizing pipe and valves in said pipes.

3. An oil burner comprising an end casting having a central opening, a slip valve projecting through said opening, a tube surrounding the projecting end of the slip valve, said tube having terminally located discharge ports, tubular burner members receiving the discharged fuel from said ports, an oil supply pipe having in its line a vaporizing tube and discharging into the slip valve, and means for heating the vaporizing tube.

The foregoing specification signed at Memphis, Tenn., this 11th day of March, 1918.

CLYDE J. McNERNY.
